UNITED STATES PATENT OFFICE.

MYRON W. RALL, OF GARDINER, MONTANA.

SNOW-SHOE.

1,156,174.

Specification of Letters Patent

Patented Oct. 12, 1915.

Application filed March 13, 1915. Serial No. 14,186.

To all whom it may concern:

Be it known that I, MYRON W. RALL, a citizen of the United States, residing at Gardiner, in the county of Park and State of Montana, have invented certain new and useful Improvements in Snow-Shoes, of which the following is a specification, reference being had to the accompanying drawings.

- 10 This invention relates to improvements in snow shoes or skees, and has for its primary object to provide improved means for preventing backward slipping of the shoe in climbing a hill.
- 15 The invention has for a more particular object to provide a gripping element pivotally and removably mounted upon the shoe and held in operative position by the engagement of the heel of the foot therewith.
- 20 The invention has for an additional object to provide a device of the above character which may be very easily and quickly applied to the shoe body or removed therefrom, is strong and durable in its construction and capable of manufacture at comparatively small cost.

With the above and other objects in view, my invention consists in the novel features of construction, combination, and arrangement of parts to be hereinafter more fully described, claimed, and illustrated in the accompanying drawing, in which,

Figure 1 is a perspective view of my improved snow shoe showing the same applied to the foot; Fig. 2 is a side elevation, the creeper attachment being shown in its inoperative position in dotted lines; Fig. 3 is a section taken on the line 3—3 of Fig. 2; and Fig. 4 is a detail perspective view of

40 the creeper device removed.

Referring in detail to the drawing, 5 designates the body of the shoe, which is preferably constructed of aluminum and is of the usual elongated form. This shoe body 45 has a central thickened portion forming a longitudinally extending ridge 5' upon its upper surface, said upper surface sloping downwardly from this central ridge to the longitudinal edges of the shoe body so that snow 50 may readily slide therefrom and thus obviate excessive weight upon the shoe. The shoe body, at its forward end, tapers to a point, and is slightly curved upwardly, as indicated at 6. In the bottom face of the 55 shoe body, at its central thickened portion, the longitudinally extending groove or

channel 7 is formed, in which snow is adapted to pack and prevent sidewise or lateral sliding movement of the shoe. The shoe body includes a wide forwardly extending portion and a relatively narrow rear portion, whereby vertical shoulders 8 are produced in the longitudinal edges of said body intermediate of its ends. Upon the upper surface of the shoe, centrally thereof, the body is formed with a raised convex portion 9 which is adapted to fit the arch of the wearer's foot. Upon the longitudinal edges of the shoe body, at the shoulders 8 thereon, a toe strap 10 is pivotally connected to the body. This strap may be formed in two sections and connected together by a suitable buckle, if desired. A transversely disposed bolt 11 extends through the shoe body at its center and is rigidly fixed therein. The ends of this bolt project outwardly from the recesses 8 and are provided with the elongated elliptical-shaped heads 12, the major axes of which are vertically disposed.

My improved creeper attachment is constructed from a single metal bar of iron or steel, indicated generally by the numeral 13. This metal bar is bent upon itself into U-shaped form, and at the curve or bend therein, the body of the bar is transversely curved, as at 14, and has its convex face inwardly disposed. One end of this bar is curved and formed with a laterally projecting gripping point 15. Each end of the bar 13 is further provided with an elongated opening 16 which is similar in outline to the shape of the bolt heads 12. The bar 13 is also provided with openings indicated at 13', to which an ankle embracing strap 17 may be connected.

In the application of the creeper device to the shoe, the ends thereof are arranged in proper position upon opposite sides of the shoe body so that the bolt heads 12 will pass through the openings 16. Upon the release of the creeper, the same will turn upon the bolt 11 and fall to the position shown in full lines in Fig. 2, the gripping point 15 projecting downwardly below the bottom face of the shoe body. The openings 16 will then be disposed at an angle with respect to the bolt heads 12 so that the creeper will not become accidentally detached from the ends of the bolt.

When the foot is arranged upon the convex portion 9 on the upper face of the shoe body, as shown in Fig. 1, the toe extends un-

der the strap 10 while the heel engages the curved intermediate portion 14 of the creeper bar. In ascending an incline, the heel presses against this curved portion of the 5 bar and effectually prevents upward movement of the same, whereby the gripping point 15 is maintained in position for gripping engagement in the packed snow or ground. A reverse or retrograde sliding 10 movement of the shoe is thus obviated, so that rapid progress may be made in the ascent. When it is desired to remove the creeper from the shoe body, the same is turned to proper position to permit the ends 15 of the creeper to be forced outwardly over the heads 12 of the bolt 11. When traveling upon a level surface and it is not desired to use the creeper, the same is simply moved forwardly to raise the point 15, as 20 illustrated in dotted lines in Fig. 2 of the drawing.

From the foregoing description, taken in connection with the accompanying drawing, the construction, manner of use, and several 25 advantages of my invention will be clearly and fully understood.

It will be seen that I have produced a very simple, effective and convenient creeper attachment for snow shoes, which may be 30 easily and quickly applied thereto or removed.

The device does not add materially to the weight of the shoe which, as above stated, is preferably constructed of aluminum. 35 However, it is also apparent that, if desired, the creeper device may be used upon wooden snow shoes.

While I have shown the preferable form and construction of my invention, it is manifest 40 that the device is susceptible of considerable modification, and I, therefore, reserve the privilege of resorting to all such legitimate changes as may be fairly embodied within the spirit and scope of the appended 45 claims.

Having thus fully described my invention, what I desire to claim and secure by Letters Patent is:—

1. The combination with a snow shoe, of a 50 creeper device pivotally mounted upon said shoe and held in effective position and against pivotal movement in one direction by the engagement of the heel therewith.

2. The combination with a snow shoe, of a 55 creeper attachment pivotally and removably mounted upon the body of the shoe and held in effective position against pivotal movement in one direction by the engagement of the heel therewith.

60 3. The combination with a snow shoe, of a creeper attachment pivotally mounted upon opposite sides of the shoe body and terminat-

ing at one end in a gripping point, a portion of the creeper extending over the top of the shoe body for engagement of the heel 65 therewith whereby the gripping point is held in its effective position.

4. The combination with a snow shoe, of a creeper attachment consisting of an elongated U-shaped bar pivotally mounted at its 70 ends upon opposite sides of the shoe body and terminating at one end in an angularly disposed gripping point, the intermediate portion of said bar extending over the top of the shoe body for engagement of the heel 75 therewith whereby the gripping point is held in its effective position.

5. The combination with a snow shoe, of a creeper attachment including a U-shaped bar, a bolt extending transversely through 80 the shoe body and projecting beyond the opposite sides thereof, said creeper bar and the bolt being provided with means for removably holding the ends of the bar in connected relation with the bolt, said bar at one of its 85 ends terminating in an angularly disposed gripping point, the intermediate portion of the bar extending over the top of the shoe for engagement of the heel therewith whereby the gripping point is held in effective position.

6. The combination with a snow shoe, of a creeper attachment including a U-shaped metal bar provided in its ends with elongated openings and terminating at one end 95 in an angularly disposed gripping point, and a bolt extending transversely through the body of the shoe and having elongated heads formed upon its ends for engagement through the openings in the creeper bar to 100 retain the ends of the bar in removable connection with said bolt, the intermediate portion of the creeper bar extending over the body of the shoe for engagement of the heel therewith whereby the gripping point is 105 held in its effective position.

7. The combination with a snow shoe, of a creeper attachment pivotally and removably mounted upon the body of the shoe, and an ankle embracing strap carried by said 110 creeper attachment.

8. The combination with a snow shoe, of a creeper attachment consisting of a U-shaped bar pivotally mounted at its ends upon opposite sides of the shoe body and terminating at one end in a gripping point, and ankle straps connected to the arms of said bar. 115

In testimony whereof I hereunto affix my signature in the presence of two witnesses.

MYRON W. RALL.
